UNITED STATES PATENT OFFICE.

FREDERICK HOWARD AULD, OF COLUMBUS, OHIO.

MEANS FOR SECURING NAME-PLATES.

1,217,263.

Specification of Letters Patent. Patented Feb. 27, 1917.

Application filed October 5, 1914. Serial No. 385,000.

To all whom it may concern:

Be it known that I, FREDERICK HOWARD AULD, a citizen of the United States, residing at Columbus, in the county of Franklin and State of Ohio, have invented a certain new and useful Improvement in Means for Securing Name-Plates, of which the following is a specification.

The object of this invention is to provide a convenient and effective means for securing a name plate or other article upon another object or structure and especially upon articles constructed of sheet metal, wood, paperboard, hard rubber or other material where a name plate is desired and can be applied. It is especially my object to provide means whereby such plates can be so secured as to render their removal difficult.

20 The invention is embodied in the example shown in the accompanying drawing and set forth in the following specification, the invention not being confined in its practical embodiment and application to the forms, materials and uses shown and stated.

In said drawings—

Figure 1 is a plan view of the face of the name plate.

30 Fig. 2 is a central sectional view of the securing member unattached to the name plate.

Fig. 3 is a similar view of the name plate without the attaching device shown in Fig. 2.

35 Fig. 4 is a central section showing the securing member applied to the name plate.

Fig. 5 illustrates the device prepared as shown in Fig. 4 placed in an orifice in an object to which the name plate is to be secured.

40 Fig. 6 illustrates the same parts as are shown in Fig. 5 but with the securing member spread into securing position.

Fig. 7 is a plan view of the rear side of 45 the device.

In the views 10 designates the name plate, one side or the face of which may be left blank or provided with any suitable symbol, ornamentation or legend or all or any of 50 these, while the other side contains, preferably, a circular boss 10^a. The name plate has its edge rabbeted as shown to form a rim 10^b and an annular flange 10^c around the

name plate. 11 designates the securing member which is best formed of sheet metal. 55 The securing member is shown as of circular form and initially of a diameter equal to or less than the diameter of the name plate at the rim 10^b. The securing member is also made with a central orifice 11^a, a flat 60 margin 11^b around the orifice 11^a and a concavo-convex rim 11^c. The securing device is placed on the name plate with the concave side of the rim facing the rear side of the name plate and with the orifice fitting 65 around the boss 10^a and the latter is spun or bent over, as shown in Fig. 4, to clench or affix the securing member to the name plate.

In applying the device to another structure, a wall of the structure such as shown 70 at 12 is provided with a through hole of substantially the diameter of the device at the rim 10^b and into this hole is inserted the device as shown in Fig. 5. A blow or suitable pressure upon the securing device is 75 then applied so as to spread the margin of the concavo-convex rim of the securing device outward over the margin of the part 12 around the hole therein, as shown in Fig. 6. The blow or pressure proposed is 80 not to be such as to entirely flatten the concavo-convex rim but should be such as to leave some convexity so as to cause the rim of the securing member to engage the face of the wall 12 with a pressure. In other words 85 the securing member is left in a state of tension pressing upon the face of the wall, binding the device to the wall with sufficient tightness to prevent its movement in any direction therein and preventing its removal except by destructive measures.

What I claim is—

Means for securing a member to another structure, consisting in the combination with such member, of a plate constituting a securing member attached to the first named member, said securing plate being concaved and adapted to be spread edgewise into tensioned engagement with a face of the structure to which the first named member is to 100 be secured.

FREDERICK HOWARD AULD.
